No. 796,601.

PATENTED AUG. 8, 1905.

J. PERRIGOT.
PAPER MAKING MACHINE.
APPLICATION FILED DEC. 14, 1904.

UNITED STATES PATENT OFFICE.

JULES PERRIGOT, OF ARCHES, FRANCE.

PAPER-MAKING MACHINE.

No. 796,601.

Specification of Letters Patent.

Patented Aug. 8, 1905.

Application filed December 14, 1904. Serial No. 236,874.

To all whom may concern:

Be it known that I, JULES PERRIGOT, paper manufacturer, a citizen of the Republic of France, residing at Arches, in the Department of Vosges, in the Republic of France, have invented certain new and useful Improvements in Paper-Making Machines, (for which application has been made in France, No. 337,911, December 21, 1903; Germany, December 29, 1903; England, No. 25,726, November 25, 1904; Belgium, November 28, 1904, and Switzerland, November 28, 1904,) of which the following is a specification.

This invention has for its object improvements in continuous paper-making machines, affording means for avoiding any deformation of the sheet and any alteration in the felting of the fibers. In fact, in order to avoid any deformation of the paper sheet it is necessary that, first, the supporting band or belt should be practically non-deformable; second, the sheet should only leave the supporting band or apron when it is completely dry. The present invention realizes these two conditions by adopting as support a fine very resistant metallic cloth or band, which carries the sheet of paper through all the drying operation.

The accompanying drawings show a dia-grammatic sketch intended to explain how the invention is put in practice in a continuous paper-making machine.

Figure 1 shows diagrammatically the draining, transferring, and drying apparatus for the paper sheet. Fig. 2 represents in dia-gram the moistening-presses interpolated at B B' in Fig. 1.

The layer of pulp drains, as in all paper-machines, through an endless metallic-cloth belt 1. When it has reached the end of this band or belt, the layer of pulp forming a sheet *a* is pressed by a drum 2, surrounded with felt 3, on which the sheet adheres. The felt 3 is stretched and guided by a series of rollers 4 in the ordinary manner. Above the drum 2 a pressing-roller 5, surrounded by a metallic cloth or band 6, is placed, which band will accompany the sheet of paper through all the drying operation. It is well not to make the sheet *a* pass directly from the metallic cloth 1 on to the metallic cloth 6, first, because the sheet directly compressed between these two cloths would retain their impression and would undergo too strong a pressure, and, secondly, because it would be detached with difficulty from one of the metallic cloths in order to

pass on to the other. On the contrary, by interposing a felt-coated drum 2 the sheet *a* passes easily from the metallic cloth 1 onto the felt 3 and from the felt 3 onto the metallic cloth 6. There is no need to fear that the sheet will suffer in its passage over the felt 3, because it must be pointed out that it is not in contact with the free part of this felt, but only with the part which is strongly pressed on the drum 2 and between the two points of contact with pressure-rollers 4 and 5. The felt 3 may, however, be dispensed with and replaced by a sleeve on the drum 2. It is in order to facilitate the cleaning of said sleeve that it is preferable to replace the sleeve by a felt fulfilling the same object.

On quitting the roller 5 the sheet of paper accompanied by the metallic cloth passes, if thought well, between one or more moistening-presses *p* and *p'* of any known system interpolated at B B', and it may be pointed out that in certain cases the damping-presses may be entirely dispensed with or in other cases their number may be diminished. The sheet of paper always supported by the metallic cloth then passes over drying-cylinders 7 8 9, &c. In its passage over the first drying-cylinders it is preferable that the sheet of paper shall not be in direct contact with the surface of the cylinders in order to avoid too sudden an evaporation, but that the metallic cloth shall be interpolated between the sheet and the surface of the cylinders. With this object the sheet and its support are caused to turn over small sleeved rollers 20. Afterward the sheet of paper and the metallic cloth are alternately in contact with the drying-cylinders, and the arrangements are made in such a way that the sheet is in direct contact with the last drying cylinder or cylinders 10, from whence it is wound on a reel 11. The metallic belt, guided by small rollers 12, returns to the roller 5 after being passed through stretching devices, belt-guides, cleaning appliances, and the like.

This arrangement furnishes the sheet of paper with a non-deformable support which accompanies it through in all the drying operation and prevents not only its unfelting, but also its elongation or crimping.

It is evident that the invention hereinbefore described with reference to a flat machine might also be applied to a round machine and that it is applicable to all kinds of paper made in continuous lengths.

I declare that what I claim is—

1. In a machine for the continuous manufacture of paper, an endless band of metallic cloth adapted to support the sheet of paper during the whole of the drying operation.
2. In a machine for the continuous manufacture of paper an endless band of metallic cloth adapted to support the sheet of paper during the whole of the drying operation and rollers guiding and supporting said band.
3. In a machine for the continuous manufacture of paper the combination with means for supporting the sheet of paper during the whole drying operation of draining means and a drum coated with felt adapted to convey the paper from the draining means to the supporting means.
4. In a machine for the continuous manufacture of paper the combination with a metallic endless band adapted to support the paper during the whole of the drying operation of an endless draining-band and a roller covered with felt intermediate said two endless bands.
5. In a machine for the continuous manufacture of paper, means for supporting the sheet of paper during the whole of the drying operation comprising an endless band, drying-cylinders supporting said band, said supporting means being located at the beginning of the drying operation between said sheet and said cylinders and said sheet being in direct contact with said cylinders toward the end of the operation.
6. In a machine for the continuous manufacture of paper comprising supporting means for the sheet of paper and drying-cylinders supporting and guiding said supporting means, means for gradually bringing said sheet into closer contact with said drying-cylinders substantially as and for the purpose set forth.
7. In a machine for the continuous manufacture of paper, an endless band adapted to support the sheet of paper throughout the whole of the drying operation, drying-cylinders and guide-rollers supporting said endless band, whereby the endless band is interposed between the sheet of paper and the drying-cylinder at the beginning of the operation and the sheet brought into direct contact with the drying-cylinders toward the end of the operation substantially as described.
8. In a machine for the continuous manufacture of paper, the combination of a non-deformable endless band for supporting the sheet of paper during the whole of the drying operation, draining means, and means for directly conveying the sheet from the draining means to the drying-band.
9. In a machine for the continuous manufacture of paper, the combination of an endless band of metallic cloth for supporting the sheet of paper during the whole of the drying operation, a metallic draining-belt, and a felt-covered roller for directly conveying the sheet from the draining-belt to the drying-band.
10. In a machine for the continuous manufacture of paper, the combination of an endless band of metallic cloth for supporting the sheet of paper during the whole of the drying operation, draining means, a felt-covered roller for directly conveying the sheet from the draining means to the drying-band, a plurality of drying-cylinders, and moistening-presses interpolated between the said conveying means and the drying-cylinders and through which the said band and paper pass before passing over the drying-cylinders.
11. In a machine for the continuous manufacture of paper, the combination of a non-deformable endless band for supporting the sheet of paper during the whole of the drying operation, draining means, means for directly conveying the sheet from the draining means to the drying-band, guide-rollers for the said band, and a plurality of drying-cylinders over which the said band passes.
12. In a machine for the continuous manufacture of paper, the combination of a non-deformable endless band for supporting the sheet of paper during the whole of the drying operation, draining means, means for directly conveying the sheet from the draining means to the drying-band, guide-rollers for the said band, and a plurality of drying-cylinders over which the said band passes, the arrangement being such that for the first of the cylinders the band is interposed between the sheet and the cylinders, for the cylinders located at the middle of the group that the band and the sheet pass alternately next to a drying-cylinder, and that the sheet is in contact with the last of the cylinders, whereby the drying effect is progressively increased.
13. In a machine for the continuous manufacture of paper, the combination of an endless band of metallic cloth for supporting the sheet of paper throughout the whole of the drying operation, a plurality of drying-cylinders around which the said band passes, and guide-rollers for said band.
14. In a machine for the continuous manufacture of paper, the combination of an endless band of metallic cloth for supporting the sheet of paper throughout the whole of the drying operation, a plurality of drying-cylinders around which the said band passes, and guide-rollers for said band, the relative arrangement of the said drying-cylinders and guide-rollers being such that in the first of the series of drying-cylinders the said band is interposed between the paper and the drying-cylinders, in the middle of the series alternately the band and the paper are in contact with the drying-cylinders, and at the end that the paper passes next to the last drying-cylinder, whereby the drying operation is gradually accelerated.
15. In a machine for the continuous manufacture of paper, the combination of a draining-belt of metallic cloth, an endless band of

metallic cloth for supporting the sheet of paper during the whole of the drying operation, a felt-covered roller for directly conveying the sheet from the draining-belt to the drying-band, guide-rollers for the said band, and a plurality of drying-cylinders over which the said band passes, the arrangement being such that at the first of the drying operation the band comes between the sheet and the cylinders, that for the middle part of the operation the band and the sheet pass alter-

nately in contact with a drying-cylinder, and that at the end the sheet comes in contact with the last of the cylinders.

In witness whereof I have hereunto signed my name, this 2d day of December, 1904, in the presence of two subscribing witnesses.

JULES PERRIGOT
